SAFETY GUARD FOR PRESSES

Edwin R. Ferrer, Fairfield, Conn., assignor to The Bassick Company, Bridgeport, Conn., a corporation of Connecticut

Application December 29, 1949, Serial No. 135,729

14 Claims. (Cl. 74—615)

1

This invention relates to safety guards for presses, and it has particular reference to guard devices for presses in which the work is placed in position in a die before being operated upon by a descending punch or plunger. The invention also has special reference to those devices having moving means for removing the hand or hands of the operator from the path of the descending punch.

Numerous devices of this general class have been proposed heretofore, but, so far as I am advised, all have been open to serious defects and disadvantages, and one of the objects of this invention is to provide an improved structure which will obviate these defects and disadvantages.

Another object is to provide a simple and relatively inexpensive structure for the purpose in view which is very sure and certain in operation.

Another object is to provide a device of this class in which there are no moving parts to obstruct the operator's view of the die, and in which the operator's hands, while under the control of flexible members attached to the operator's wrists, have very considerable freedom of movement, except at the time the punch is descending and is close to the hands, at which time the operator's hand, if in the danger zone, will be removed therefrom in a sure and effective manner.

Another purpose of the invention is to provide an improved mechanism of this type in which the moving guard device or devices are not in continuous operation, but on the other hand are operated only in case of emergency, thus decreasing the maintenance cost of the device.

In the accompanying drawings:

Fig. 1 is a front elevation of a press equipped with a safety guard embodying the invention, the punch carried by the press gate and the die being omitted;

Fig. 2 is a side elevation of the device shown in Fig. 1, the guard device being shown in a non-emergency position, the press gate being in its uppermost position, the lowermost position of the gate being shown in dotted lines;

Fig. 3 is a top plan view of the device;

Fig. 4 is a view similar to Fig. 2, the guard device being shown in the position which it assumes just before the operator's hand is moved automatically out of the danger zone;

Fig. 5 is a section on line 5—5 of Fig. 3;

Fig. 6 is a sectional view showing a modified form of device; and

2

Fig. 7 is a sectional view showing a further modified form.

In the device selected for illustration in Figs. 1 to 5, inclusive, the press is of the type in which the punch or plunger is carried by a gate or ram actuated by a shaft having a crank connected to the gate or ram by means of a connecting rod or pitman. The connecting rod head that is connected to the crank portion of the operating shaft is equipped with a forwardly projecting member co-acting with a tongue-shaped cam fixed to a rock shaft mounted in bearings supported by brackets from the press frame adjacent the front face of the frame. The rock shaft has connected thereto a pair of swinging arms the upper ends of which are suitably fastened to the shaft, the lower ends of said arms being connected by flexible members with wristlets attached to the wrists of the operator, the arrangement being such that the operator's hands are permitted considerable freedom and all necessary movement in feeding the work to the press and removing it therefrom, although, if the operator's hand is in the path of the ram, the 10 projection on the connecting rod head, in conjunction with the tongue-shaped cam on the rock shaft, will act in such a manner as to swing the depending arms, and thereby the operator's hands, in an outward direction and out of the 15 path of the ram when the ram reaches a certain point in its movement. The depending swinging arms just referred to are in locations adjacent the respective sides of the press frame, and when the rock shaft is turned they swing 20 in a generally forward and rearward direction. Their forward and rearward movement is under the guidance of forwardly extending guide elements in the form of bars generally horizontally disposed and having ends adjacent the press frame that are fastened to the press frame for 25 swiveling movement, as hereinafter described. These bars are at the inner sides of the swinging arms, and the swinging arms are arranged to 30 make contact therewith so that the arms are 35 guided and are held separated at a minimum 40 distance.

In the drawings, the press frame is indicated at 45 10, the press bed at 11, the ram or gate at 12, the connecting rod at 13, the connecting rod head at 14, the driving shaft at 15, and the crank to which the head 14 is connected, at 16. The rock shaft, previously mentioned, is indicated at 17, the brackets which mount the rock shaft from the forward face of the press frame at 18, the 50 depending swinging arms fastened at their upper 55

ends to the rock shaft, at 19, the forwardly projecting guide bars at 20, the wristlets adapted to be fastened to the wrists of the operator, at 21, and the flexible members (shown as chains) connecting the wristlets to the lower ends of the arms 19, at 22. In the present case, a single spring 23, connected at one end to a part on the rock shaft and at the other end to the left-hand bracket 18 (Fig. 1), holds each of the swinging arms normally in the position shown in Fig. 2.

The punch carried by the press gate and the tool block or die-holding block with which the punch cooperates are shown in Fig. 2, but are omitted in the other views. The connection of the connecting rod to the press gate or ram is not shown in detail, but it is understood that the lower end of the connecting rod has proper pivotal connection with the ram or gate.

In the embodiment shown, there are two mounting brackets for the rock shaft 17, these being disposed adjacent the respective sides of the press frame. To each of these brackets is attached, as by means of the bolt 24, a bearing member 25 in which the rock shaft has a bearing at a point between its middle portion and its extremities. As shown in Fig. 1, the rock shaft projects to the right and left beyond the bearing members, and the swinging arms 19 are carried by the rock shaft outwardly from the bearing members. Each of the arms 19, which can be conveniently made of tubular metal stock, is attached by means of a screw 26 to a collar 27 that is rigidly fastened as by screws 28 to the rock shaft, the arrangement being such that, as the rock shaft is turned in its bearings, the arm 19 is swung forwardly or rearwardly as the case may be. The arm 19 is rigid with the rock shaft transversely of the shaft but is free to swing lengthwise of the shaft, the connection of the arm to the collar 27 by means of the screw 26 being a pivotal connection. Screw 26 passes through an aperture in the arm, and is set up so that the arm can swing as above mentioned, and follow the angle of the guide bar 20. A set screw 26^a in the collar 27 fixes the screw 26 in the proper position and prevents it from working loose after adjustment. The guide bar 20 is swiveled at one end to the press frame, and for this purpose the guide bar proper has welded thereto at the end adjacent the press frame a vertical swiveling pin 29 that is engaged in a swiveling socket 30 formed in a bracket 31 that is attached in a suitable manner, as by bolts 32, to the front face of the press frame. In this manner there is provided an upright pivot member for the guide bar enabling the bar to be swung to any of a number of different angular positions in a horizontal plane. After the bar has been adjusted to the desired position it can be fixed in this position as by means of set screws 33 associated with the swiveling socket that can be screwed inwardly to clamp the swivel pin against movement.

When the guide bars 20 are in the position shown in full lines in Fig. 3, the arms 19 will swing in vertical planes transverse to the rock shaft, but when the guide bars are swung angularly, as indicated for example by the dotted lines at the right of Fig. 3, the arms 19, in moving forwardly and rearwardly, will swing in planes which are tipped or tilted with respect to the vertical.

It is not desirable that the arm 19 be swung to an excessive angle longitudinally of the rock shaft, and for limiting this adjustment suitable

means are provided in association with the ends of the rock shaft. In the present case each end of the rock shaft has fastened thereto, by means such as a fastening screw 34, a forwardly projecting stop plate 35 in the forward end of which is carried an adjustable stop screw 36 provided with a lock nut 37. This screw 36 has an extremity projecting through the stop plate 35 toward the side of the corresponding swinging arm 19 and adapted to be contacted by the side portion of the swinging arm at a point somewhat below the upper pivotal connection of the arm with its mounting collar. This pivotal connection between the arm and the mounting collar is provided by having the screw 26 pass through an aperture in the upper flattened extremity of the arm. By the arrangement described the inner end of the stop screw 36 is engaged by the swinging arm in a manner to limit movement of the arm generally longitudinally of the rock shaft, and by adjusting the screw 36 the permissible angular shift of the arm lengthwise of the rock shaft can be adjusted as desired.

For the purpose of permitting some adjustment of the rock shaft toward and away from the opposing face of the press frame, the brackets 18 may have slots 38 in their lower or horizontal legs 39 in which the bolts 24 for supporting the rock shaft bearings are adjustable. This is of advantage in permitting adjustment in the cam connection provided between the rock shaft and the upper end portion of the connecting rod head, which connection is described at a later point. For facilitating effective clamping of the rock shaft bearings in place, washers 40 underlying the nuts 24^a on the bolts may have roughened or serrated surfaces engaging the bracket parts 39.

In order to limit endwise movement of the rock shaft in its bearings, thrust collars 41 and 42 may be rigidly fastened on the shaft adjacent the inner sides of the bearing members 25. For the purpose of limiting the forward swing of the depending arms 19, suitable means are provided. In the present instance this means comprises a stop bar 43 which is tangentially arranged with respect to the thrust collar 42 and is welded to the thrust collar. The disposition of the stop bar relatively to the thrust collar is as shown in Fig. 5, and the arrangement is such that, when the arm 19 is swung outwardly to the position shown in Fig. 2, the upper end of the stop bar engages the forward extremity of the adjacent bracket 18 for the purpose of arresting movement of the arm. While this is the preferred arrangement, other means may be used for arresting the forwardly swinging arm 19 at the desired point.

Referring now to the cam mechanism between the connecting rod head and the rock shaft, it will be noted that in the form illustrated the upper end of the connecting rod head 16 is provided adjacent its front face with a bracket 44 carrying at its forward end a roller 45 that is adapted to engage a tongue-shaped cam member 46 fixed to the rock shaft at the central portion of the rock shaft. The member 46 has an upper portion 47 in the form of a split ring or band embracing the rock shaft and adapted to be clamped fixedly in the desired angular position thereon by a clamping bolt 48. Projecting downwardly from the ring portion or band portion of this member is the tongue portion or depending cam arm of the member, which tongue portion is curved forwardly and downwardly with reference to the drive shaft of the press, as shown for

example in Fig. 2. The roller 45 will not make contact with the member 46 when the hand of the operator is kept out of the path of the descending punch, but if the hand is in the position shown in Fig. 4, for example, where it is under and in line with the punch, the member 46 will be engaged by the roller 45, with the result that the arm 19 will be kicked outwardly to remove the hand from danger. The extreme upper position of the connecting rod head is shown in full lines in Fig. 2, and the extreme lower position in dotted lines, and the path of the roller axis is indicated here by the arrow, and it will be apparent that, if in handling the work in the press the operator causes the arm 19 to be moved to a position where the tongue 46 will be in the roller path, the safety device will be actuated to pull the hand out of danger.

The spring 23, previously mentioned, is in this particular case interposed between a part on the rock shaft and a portion of the left-hand bracket 18 (Fig. 3). This spring is shown as a wire spring having an intermediate coil 23^a and branching ends 23^b. One end is secured to the upright part of the adjacent bracket 18 by means of a screw 49. The other extremity of the spring is secured by a screw 50 to a radial projection 51 on a collar 52 rigidly fixed to the rock shaft at one side of said bracket. When the arm 19 is moved to the position of Fig. 4, the coil of the spring 23 is tightened, and the spring further energized. Normally, however, the spring holds the stop bar 43 against its cooperating bracket (Fig. 2).

The guide bars 20 may be made conveniently of tubular metal stock and at their forward end portions they are preferably curved upwardly on a gentle curve, as shown.

The wristlet 21 is provided with a loop 21^a extending forwardly and adapted to be held in place between the thumb and the index finger of the operator, the purpose being to hold the wristlet in a definite position on the person's wrist or arm.

In the modified form shown in Fig. 6, the device is particularly adapted for use on a straight long-stroke press, and here the cam mechanism for kicking out the swinging side arm involves a contactor member 53 which is rigidly attached to the press gate 54. The contactor 53 is adapted to kick out the side arm by making contact with the knee portion 55 of a rod 56 that is adjustable longitudinally in a clamp 57 rigid with a member 58 that is rigidly clamped to a rock shaft 59 corresponding to the rock shaft 17 previously described. The clamp 57 has a bore in which the rod 56 is received, and screws 60 are adapted to clamp the rod in adjusted position in the bore. By this arrangement the device can be set so that the fixed camming contactor on the press gate will, by engaging the camming rod or depending cam arm 56, actuate the swinging side arms in the proper manner, as previously described. The side arms may have the same arrangement with respect to rock shaft 59 as heretofore described.

In the modified form shown in Fig. 7, which is particularly adapted for use on a straight medium-stroke press, the contactor 61 on the press gate is adapted to make contact with a depending cam arm member 62 clamped to the rock shaft 63. In this case the member carried by the rock shaft is a non-adjustable member so far as the camming action is concerned, but the contactor 61 is adjustable in a vertical direction on the press gate. For this purpose the press gate

may be equipped with an outstanding plate 64 spaced from the gate and having a vertical slot 65. The contactor 61 is rigid with a plate 66 positioned against the forward face of the plate 64 and vertically adjustable by means of clamping bolts 67 passing through the slot 65.

It will be evident that the described structure includes a rock shaft applied to the forward face of the press in a location substantially above the location of the work and having attached to the rock shaft depending swinging side arms having at their lower ends flexible connections to the arms of the operator for pulling the hands out of the danger zone, there being between the rock shaft and the upwardly and downwardly moving working element of the press a cam mechanism acting as a kick-out device which, if the operator's hands are in the danger zone as the press punch approaches them, kicks the side arms forwardly in a positive and rapid manner so as to pull the hands from the danger zone with all of the force required for the purpose. The spring will tend to pull the side arms forwardly and normally will maintain the cam member on the rock shaft clear of the cooperating camming member, but will not exert too much restraint upon the operator's arms. The kick-out action, it will be noted, takes place against a portion of the cam mechanism which is comparatively close to the rock shaft in the forms of Figs. 1 and 7, respectively, and somewhat farther away from the rock shaft in the form of Fig. 6.

It is a point of distinct advantage that the safety device, embodying the swinging guard arms and the cam mechanism operable from the press, is not in continuous operation by the press but is operated only in case of emergency, because this effects a large decrease in the cost of maintenance.

The device is of relatively simple and inexpensive structure, and yet is susceptible of adjustment in order to meet different conditions of use, and when the device is in use it does not interfere with the operator's access to the work, nor does it obscure the operator's view of the work, nor is it likely to cause injury to the operator's hands by striking or bruising them. A very considerable advantage also arises from the fact that the swinging side arms are clear and free of the space between the plunger and the die at all times, and are maintained by the guide bars in their proper zones of operation, and are prevented from swinging inward from their prescribed positions, as adjusted, and that the side arms, when the gate is descending and the operator's hands are in the danger zone, and only at that time, pull with sufficient (and ample) force on the hands to move them to safety, the action under such circumstances being a positive one as well as a rapid one.

Where reference is made to the operator's hand being in the path of the ram, the term "ram" is used in a broad sense so as to apply to a ram structure carrying a punch or like element likely to cause injury to the operator's hand.

Various changes in the organization of parts and in the details may be made without departing from the principles of the invention or the scope of the claims.

What I claim is:

1. In a machine of the type described having a ram or gate vertically movable in a frame and having a bed below the ram adapted to hold a workpiece to be operated upon, a pair of arms

having upper ends swingingly mounted at the front of the frame at an elevation above the work and having lower ends flexibly connected to wristlets, said arms being adapted to swing forwardly and rearwardly at the sides of the ram, means for guiding the lower end portions of said arms in a forward and rearward direction, and means operatively connecting a moving part of the press with the upper ends of said arms to swing the arms forwardly, said means being operable only when the operator's hand is in the danger zone under the ram and when the ram has descended to a predetermined point.

2. In a machine of the type described having a ram or gate vertically movable in a frame and having a bed below the ram adapted to hold a workpiece to be operated upon, a pair of arms having upper ends swingingly mounted at the front of the frame at an elevation above the work and having lower ends flexibly connected to wristlets, said arms being adapted to swing forwardly and rearwardly at the sides of the ram, means for guiding the lower end portions of said arms in a forward and rearward direction, and means operatively connecting a moving part of the press with the upper ends of said arms to swing the arms forwardly, said means being operable only when the operator's hand is in the danger zone under the ram and when the ram has descended to a predetermined point, said means including a camming mechanism having operative engagement of parts thereof by which the arms are kicked forwardly.

3. In a device such as described, the combination with a press having a bed, an upwardly movable ram, and a guide frame for the ram, of a horizontal rock shaft mounted from the frame at the front of the press, side arms having upper ends transversely rigid with the rock shaft and having lower ends flexibly connected to the operator's hands, a cam device for operatively connecting said rock shaft with an upwardly and downwardly movable part of the press at the front of the press, said cam device being operable to kick said arms forwardly when the ram has descended to a certain point and when the operator's hand is in the path of the ram, and a spring acting on said arms and tending to hold the arms in a position in which the operator's hands will be out of the path of the ram.

4. In a device such as described, the combination with a press having a bed, an upwardly movable ram, and a guide frame for the ram, of a horizontal rock shaft mounted from the frame at the front of the press, side arms having upper ends transversely rigid with the rock shaft and having lower ends flexibly connected to the operator's hands, a cam device for operatively connecting said rock shaft with an upwardly and downwardly movable part of the press at the front of the press, said cam device being operable to kick said arms forwardly when the ram has descended to a certain point and when the operator's hand is in the path of the ram, a spring acting on said arms and tending to hold the arms in a position in which the operator's hands will be out of the path of the ram, and forwardly projecting guide bars at the sides of the ram which guide the lower ends of said arms as said ends move in a forward and rearward direction.

5. In a device such as described, the combination with a press having a bed, an upwardly movable ram, and a guide frame for the ram,

of a horizontal rock shaft mounted from the frame at the front of the press, side arms having upper ends in pivoted relation to the rock shaft to swing lengthwise of the shaft and having lower ends flexibly connected to the operator's hands, a cam device for operatively connecting said rock shaft with an upwardly and downwardly movable part of the press at the front of the press, said cam device being operable to kick said arms forwardly when the ram has descended to a certain point and when the operator's hand is in the path of the ram, a spring acting on said arms and tending to hold the arms in a position in which the operator's hands will be out of the path of the ram, and forwardly projecting guide bars at the sides of the ram which guide the lower ends of said arms as said ends move in a forward and rearward direction, said guide bars being mounted on the press so as to be swingable in a substantially horizontal direction.

6. In a machine of the type described having a vertically moving ram or gate above a bed on which work is placed for tool operation, the ram or gate being guided in the machine frame, a horizontal rock shaft mounted adjacent the forward face of the frame, depending swinging side arms fastened to said rock shaft and having their lower ends flexibly connected to the hands of the operator for pulling the hands out of the path of the ram, guide bars projecting forwardly from the face of the machine frame contacting with the lower parts of said side arms and interposed between the side arms, and cam mechanism between the rock shaft and a moving part of the machine for kicking the side arms in an outward or forward direction when the operator's hand is in the ram path and the ram reaches a certain point in its movement.

7. A machine as defined in claim 6, in which the side arms are fastened to the rock shaft so as to be tiltable to move in planes inclined to the vertical and in which the guide bars are swiveled adjacent the machine frame and are adjustable horizontally.

8. A machine as defined in claim 6, in which the lower ends of the side arms are adjustable outwardly and laterally with respect to each other, and in which the rock shaft is provided with adjustable stop means at the ends of the rock shaft whereby the adjusting movement of the side arms is limited.

9. In a machine of the type described having a vertically moving ram or gate above a bed on which work is placed for tool operation, the ram or gate being guided in the machine frame, a horizontal rock shaft mounted adjacent the forward face of the frame and having bearing members adjustable toward and away from the frame, said bearing members being carried by brackets applied to the face of the frame, depending swinging side arms fastened to said rock shaft and having their lower ends flexibly connected to the hands of the operator for pulling the hands out of the path of the ram, a spring having a middle loop and branched end portions, one of the end portions being connected to one of said brackets and the other end portion being connected to a part rigid with said rock shaft, said spring tending to hold said side arms normally in positions in which the operator's hands are out of the path of the ram,

a stop member in the form of a bar fixedly applied to a member rigid with said rock shaft, said bar being adapted to engage one of said

brackets so as to limit the forward and outward swing of said arms, and mechanism between the rock shaft and a moving part of the machine for kicking the side arms in an outward or forward direction when the operator's hand and the ram are in certain positions.

10. A machine such as described, comprising forwardly and rearwardly swingable side arms at the sides of the machine adapted to pull the operator's hands out of the danger zone, said arms being movable in vertical planes at the sides of the machine and being adjustable so that they can be placed in inclined planes, and adjustable forwardly projecting guide bars contacting the lower portions of said arms.

11. In a machine of the type described having a vertically moving ram or gate above a bed on which work is placed for tool operation, the ram or gate being guided in the machine frame, a horizontal rock shaft mounted adjacent the forward face of the frame, depending swinging side arms fastened to said rock shaft and having their lower ends flexibly connected to the hands of the operator for pulling the hands out of the path of the ram, stop means in connection with the rock shaft and the rock shaft mounting for arresting the side arms when they reach a predetermined forward position, a spring normally holding the side arms in said predetermined forward position, guide bars projecting forwardly from the face of the machine frame contacting with the lower parts of said side arms for guiding the same and interposed between said side arms, and mechanism interposed between the rock shaft and a moving part of the machine for kicking the side arms in an outward or forward direction when the operator's hand is in the ram path and the ram reaches a certain point in its movements.

12. In a machine of the type described, having an upstanding frame comprising side members and a vertically moving ram or gate between said side members and above a bed on which work is placed for tool operation, a horizontal rock shaft at the front of the machine above the bed, bearing members on said frame members in which said shaft is mounted for oscillating movement adjacent the forward face of the frame, side arms fastened to said rock shaft beyond and outwardly of said bearings at the sides of the

machine and depending from said shaft and having their lower ends flexibly connected to the hands of the operator for pulling the hands out of the path of the ram, and mechanism between the rock shaft and a moving part of the machine comprising a downwardly and inwardly curved tongue or cam arm fixed on the shaft intermediate of the ends of said shaft and between the side members of said frame coacting with a roller on said moving part to kick the side arms in an outward or forward direction with respect to said bed when the operator's hand is in the danger zone under the ram and the ram reaches a predetermined position.

15. 13. In a machine of the type described, having a ram or gate vertically movable in a frame and having a bed below the ram adapted to hold a workpiece to be operated upon, a rock shaft disposed horizontally adjacent the forward face of the frame and arranged to oscillate in bearings on the frame, a side arm fastened to said shaft at one side of the machine and depending from said shaft and having its lower end flexibly connected to the hand of the operator for pulling the hand out of the path of the ram, said arm being fastened to said shaft so that the arm in moving generally forwardly and rearwardly can have a certain amount of lateral swing, means engageable by the inner side of the arm for guiding the lower end of said arm in a forward and rearward direction, and mechanism between the rock shaft and a moving part of the machine for kicking said arm in a forward direction when the operator's hand is in the danger zone under the ram and the ram reaches a predetermined position.

30 14. A machine as defined in claim 13, in which the rock shaft has associated therewith means for limiting the lateral swing of the arm.
